Inventor:
Edward B. Griffin,
by Walter G. Lomard, Atty.

UNITED STATES PATENT OFFICE.

EDWARD B. GRIFFIN, OF SOMERVILLE, MASSACHUSETTS.

RAILWAY SPIKE.

Application filed December 2, 1927. Serial No. 237,177.

This invention relates to spikes for securing rails to a tie plate and has for its object the production of a spike having one or more shoulders thereon adapted to engage the under face of a tie plate when its head is in engagement with the flange of a rail, thereby preventing the accidental displacement of the spike.

This object is attained by the mechanism illustrated in the accompanying drawing.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a tie plate such as is used with my improved railway spike.

Figure 2 represents a vertical section of the same and a rail surmounted thereon and secured thereto by spikes embodying the principles of the present invention.

Figure 3 represents a vertical section on line 3, 3, on Fig. 2, and

Figure 4 represents a vertical section on line 4, 4, on Fig. 2.

Similar characters indicate like parts throughout the several figures of the drawings.

In the drawings 10 is a tie plate of usual construction provided with a plurality of square holes 11 to receive spikes by which the tie plate may be secured to the tie 12 and the rail 13 secured to said tie plate.

As shown in the drawings the upper face of the tie plate is inclined upwardly toward the upwardly extending rib 14 against which a flange 15 of the rail 13 abuts.

Two of the holes 11 extend through the rib 14 and the thickest part of the tie plate while the other holes 11 extend through a thinner part of the tie plate.

The main purpose of the present invention is to construct a spike 16 of such a shape that it is adapted for insertion in either of the holes 11 and when so inserted it will effectually clamp the rail 13 to the tie plate 11 and will be so locked to the tie plate that

it can only be dislodged by using considerable force.

The spike 16 has a head 17 projecting from one side thereof the under face of which is inclined to correspond with the inclination of the upper face of a rail flange 15.

From one side of the spike projects a shoulder 18 which is adapted to engage the under face of the tie plate 11 when the spike has been driven into the tie 12.

The shank of the spike 16 with its shoulder 18 thereon is designed to closely fit a hole 11 through which it must be driven into the tie 12, the walls of the hole acting as a guide and insuring that the spike shall be driven straight.

When the shoulder 18 passes the under face of the tie plate 11, it will ordinarily engage said under face but to positively insure this engagement the opposite face of the shank of the spike is provided with an inclined face 19 which, as the shoulder 18 about reaches the under face of the tie plate, will come into contact with wall of the hole 11 and move the spike laterally a slight distance so that said shoulder will extend beneath the tie plate.

This shoulder 18 is located a distance from the head 17 equal to the thickness of the rail flange 15 and the tie plate 11 at this particular point.

When thus inserted it is impossible for the spike to move in either direction.

On another side of the spike is another shoulder 20 which preferably is perpendicular to the shoulder 18 and this shoulder 20 is nearer the head 17 as shown in the drawings.

In other words the shoulder 20 is positioned a distance from the head equal to the thickness of the rail flange and the thinner part of the tie plate.

When the spike is driven into a hole 11 adjacent the rib 14 the shoulder 18 will engage the under face of the tie plate and when the spike is driven through a hole 11 near the edge of the tie plate the shoulder 20 will engage said under face.

It is obvious that two sets of spikes are not required as the same spike may be used in either hole 11.

When these spikes are used in connection with a tie plate it will be impossible for the rails 15 to spread or turn over.

Moreover, as the shoulders 18, 20, engage the under face of the tie plate after being driven it is impossible for these spikes to move or work out of place.

6 Railway ties are now treated with creosote to lengthen the life thereof but this creosote acts as a lubricant making it easier for a spike to loosen and move upwardly and when this occurs the head 17 will move 10 away from the flange of the rail 13 and the latter will not be securely held which is a great disadvantage and may cause serious accidents.

This loosening of the spikes is due to jar 15 or vibration of cars or trains passing over the rails.

With my improved spike in use this disadvantage is entirely overcome as the shoulders 18, 20, absolutely prevent any upward movement of the spikes.

These shoulders 18, 20, are rounded off slightly to permit the removal of the spikes by claw bars or other similar devices when it is desired to substitute new rails for old 25 ones or for any other reason.

The side and back shoulders formed on the spike will guide the spike straight when being driven and as a consequence the entire bottom of the head 17 will contact the 30 upper face of the flange of the rail, and this is not the case when ordinary spikes are used as very often they are not driven straight and only a portion of the bottom of the head rests on the flange of rail.

35 It is believed that the operation and many

advantages of the invention will be understood without further description.

Having thus described my invention, I claim—

1. A railway spike formed with a head to engage the flange of a rail and having on two sides thereof shoulders perpendicular to each other and at different distances from said head, one shoulder being adapted to engage the under face of the thinnest part 40 of a tie plate while the other shoulder is adapted to engage the under face of the thickest part of said plate.

2. A railway spike formed with a head to engage the flange of a rail and having on two sides thereof shoulders perpendicular to each other and at different distances from said head, said shoulders being curved downwardly, one shoulder being adapted to engage the under face of the thinnest part 45 of a tie plate while the other shoulder is adapted to engage the under face of the thickest part of said plate.

3. A railway spike formed with a head to engage the flange of a rail and adapted for 50 insertion through a hole in a tie plate, said spike having a plurality of shoulders thereon at different distances from said head and either of which is adapted to engage the under face of said tie plate when said head 55 is in contact with said rail flange.

Signed by me at 746 Old South Bldg., Boston, Mass., this 1st day of December, 1927.

EDWARD B. GRIFFIN.
